PICTORIAL DISPLAY APPARATUS

Application filed April 4, 1931. Serial No. 527,766.

This invention relates to an improved means for controlling and timing the rotation of pictorial cylinders in a panoramic pictorial display apparatus such as shown in my 5 application for Letters Patent, filed March 28, 1931, Serial Number 526,003, in which a plurality of pictorial cylinders are frictionally mounted on the shaft, so that all can be simultaneously rotated by the shaft, if desired, and yet any of the cylinders can be temporarily held from such movement.

To that end this invention provides means for giving all the cylinders simultaneous intermittent rotary movement to bring into 15 view a panorama, which movement is followed by a viewing period during which the cylinders are at rest; and also means for holding temporarily any of said cylinders as desired, and thus to change the panorama 20 and cause the rotation of the cylinders in any desired sequence.

One feature of this invention consists in providing means for holding any cylinder from rotary movement as long as desired to 25 change the panorama or emphasize any picture. This holding means includes cams driven by a single shaft and said cams independently adjustable or mechanically changing the timing for interrupting the rotation 30 or releasing of any of the cylinders.

Another feature of the invention consists in a series of mutilated gears driven from one source of power for intermittently driving the shaft on which the cylinders are frictionally mounted, and also for intermittently driving the shaft on which cams are mounted for controlling the cylinder holding means. The cams have means for providing each with an uninterrupted periphery for 40 controlling the cylinder holding means, or with a sectional periphery of equal segments, or any desired number of segments, as desired for the timing and sequence of the cylinder movements.

45 The full nature of said invention will be

understood from the accompanying drawing and the following description and claims.

In the drawing, Fig. 1 is an elevation of an end portion of a series of pictorial cylinders and cylinder holding means and gearing for 50 driving the same, parts being broken away and parts being omitted. Fig. 2 is a side elevation of the cylinders and gearing shown in Fig. 1, omitting the frame, and parts being broken away. Fig. 3 is a side elevation 55 of one of the mutilated gears as seen from line 3—3, Fig. 1, the shaft being shown in section. Fig. 4 is a section on line 4—4 of Fig. 1, showing the holding bar in inoperative position, parts being broken away. Fig. 5 is a section 60 on the line 5—5, Fig. 4.

There is shown in Fig. 1 an end portion of a series of pictorial cylinders 10 frictionally mounted on the shaft 11 so that said shaft will cause all of said cylinders to revolve except 65 such as may be held from revolution. Said cylinders may be independently and temporarily held as hereinafter explained.

These cylinders, as shown in Fig. 2, are hexagonal and each cylinder has an end wall 70 10 and six longitudinal frame bars 210 in the nature of angle irons, as seen in Fig. 2, and a pictorial face or sheet 310 on which any desired picture, advertisement or the like may be placed between said frame bars, or be removed therefrom, as desired. The invention, however, is not limited to the number of pictorial faces or sheets, or whether the cylinders be hexagonal or otherwise angular in shape. Preferably, the pictorial sheets 310 are transparent and illumination is provided within the cylinder which, however, is not here shown. Nor is the complete framework of the machine shown herein, excepting that the shaft 11 is mounted in the frame bars 12 in 80 Fig. 1, and also the cam shaft 12 and drive shaft 15.

The gearing consists of a driving shaft 15 which receives power from a source, not shown, and has secured thereon a mutilated 90

gear 16 adapted to mesh with the gear 17 which is secured on and drives the shaft 11 in the direction of the arrow in Fig. 2.

The segmental gear 16 has teeth for only 5 60° or one-sixth of its circumference. The gear 17 has teeth entirely around it, but is driven by the drive shaft 15 for only one-sixth of the revolution of said drive shaft, the remaining five-sixths of the revolution of the 10 drive shaft leaving shaft 11 and the cylinders at rest. In this way the cylinders as a plurality or unit are given a sufficient rotation to turn the front longitudinal row of pictorial faces 310 up out of the way and bring into 15 view another row of faces 310, which are in view during the remaining five-sixths of the slow rotation of the shaft 15, and then another row of faces 310 are moved into view.

It must be understood that the driving 20 shaft 15 operates comparatively slowly so as to leave the row of pictorial faces 310 in view a sufficient length of time for the same to be satisfactorily viewed.

The foregoing gearing would intermittently 25 operate all the cylinders simultaneously and to the same extent, but in order to vary the panoramic series of pictures it is desired to hold some of the cylinders so as to make a new combination of pictures in the panorama 30 or give longer view of some pictures as desired. The means for accomplishing said result will now be explained.

Below the cylinders 10 and shaft 11 there is a cam shaft 13 on which there is secured a 35 cam 20 under each cylinder. The purpose of each of these cams is to lift the holding plunger 21 from its disengaging position, as shown in Fig. 4, into a position to engage one of the corner frames 210 of one of the cylinders 10, as shown in Fig. 1, and thus stop it and hold it temporarily. This stop means is provided for each cylinder and is controlled by the gearing and cams. The cam shaft 13 is driven by the shaft 15 through the train of 45 gears 35, 36, 37 and 38. The gears 36 and 37 are mounted on a jack shaft 50 journaled in the frame bars 12.

Each holding plunger 21 is vertically movable in its stationary guide plate 22. Its 50 downward movement is limited by the collar 23 engaging said bar 22, as seen in Fig. 4. Its upward movement is caused by the cam 20 on the periphery of which it rests or rides. The holding plunger 21 is held down in the 55 position shown in Fig. 4 by a spring 24 coiled around said plunger and at one end bearing against the stationary plate 22 and at the other end against a pin 25 in said plunger 21. The upper end 221 of the holding plunger is 60 forked, as shown in Fig. 4, so as to not only engage the frame bar 210 but hold the cylinder from rotation when it is up in the position shown in Fig. 1.

Each cam wheel 20 has a series of recesses 65 26 in its periphery, one for each side of its

respective cylinder. Therefore, there are six of said recesses equidistant in the rim of the cam wheel. The following edge of each recess 26 is curved from the bottom thereof outwardly to the outer periphery of the cam wheel, and the following edge is inclined; and the recess is wide enough to allow the heel 120 of the holding plunger 21 to enter the same freely and so formed as to be capable of riding up the inclined curved face of the recess to the normal periphery of the cam. 70 75

When the heel of the holding plunger 21 is in the recess 26, as seen in Fig. 4, its respective cylinder is released and will revolve with the shaft, but when the cam wheel is turned to cause the heel of the holding plunger 21 to ride up out of the recess onto the periphery of the cam wheel, the forked end of the holding plunger 21 will be brought into holding engagement with its respective cylinder, 80 as shown in Fig. 1, and that will hold the cylinder from rotation until further rotation of the cam wheel in the direction of the arrow in Fig. 2 enables the heel 121 of the holding plunger 21 to drop down into the following recess and release the forked end 221 from the cylinder, as seen in Fig. 4. 85 90

The recesses 26 and the function of same are obviated by segmental cam plates 27 pivoted at 28 to a side of the cam wheel 20 in position so the outer or arcuate portion of the plate may register with the periphery of the wheel, as shown at *a* in Fig. 4 and as illustrated in Fig. 5, and said plate is yieldingly locked in such position by the spring 29 acting against a rounded head 30 that forces it into a notch 31 in the side of the cam wheel 20, as seen in Fig. 5. This will hold the plate 27 in its adjusted closed position until it is manually changed and moved out of the way, as is also true of the five plates 27 shown in Fig. 4. 95 100 105

If all the plates 27 are moved so their cam surfaces are aligned with the periphery of the cam wheel 20 the heels 121 of the plungers will be held out of the recesses 26 when the wheel is revolved by means of the toe 321 riding on the cam surface of the plates 27, thereby causing the forked end of the plunger to engage its respective cylinder and keep it from rotating, as seen in Fig. 1, until the plates 27 are again adjusted so the heels 121 can again enter the recesses. It is obvious that one or more of the plates 27 can be adjusted to stop the rotation of their respective cylinder for a predetermined period during the rotation of the cam wheel. 110 115 120

Thus in the machine shown herein the timing might be as follows: The cylinders 10 could be revolved by the shaft 15 and mutilated gear 16 for one-sixth of a revolution, or 60° , and for two seconds while the teeth in gear 16 mesh with the teeth in gear 17. That would move the visible pictorial illustrations 310 out of the way and would bring another 125 130

row into view and they would remain in view for five-sixths of a revolution of the shaft 15, gear 16 and cylinders, or for ten seconds. Then the cylinders would be given a one-sixth 5 revolution for two seconds, and this process would be repeated. However, by changing the gearing on the multilated gears, the timing of the cylinders could be correspondingly changed. The timing above described would 10 give individuals ten seconds to view the pictures that the machinery in two seconds had brought into view, and, as stated, that time could be altered.

Likewise the gearing operating the cam 15 wheels 20 would give to said cam wheels the movement corresponding to that given to the cylinders. Thus the gears 37 would be operated the same as gear 16 and turn the gear 20 38 and cam shaft 13 one-sixth of a revolution, say, for two seconds, and then the cams and cam shaft would be idle for five-sixths of a revolution or ten seconds.

By relatively changing the different cam wheels 20 through the instrumentality of 25 their cam plates 27, the cam wheels could cause the cylinders to be held or released from rotation according to any desired sequence. A single wheel 20, if the cam plates were adjusted as shown in Fig. 4, would release its 30 corresponding cylinder at the end of every 60° movement of the cam, except during one segmental movement thereof its cylinder would be held at rest for almost 120°. If all of the plates 27 were turned so as to close 35 the notches in the cam plate, it would hold the cylinder locked at rest until the cam plates were readjusted.

Hence, there is a wide range of adjustment 40 of the cams and holding means. While the holding plunger 21 is forked at its upper end, that is not necessary as only one side of the fork functions by resisting the tendency of the cylinder to rotate. In the form shown in 45 Fig. 4, it is the left hand branch of the fork that holds the cylinder from rotation, but the fork has its advantage by way of centering the cylinder.

I claim as my invention:

1. Pictorial display apparatus, including a 50 shaft, a plurality of individual pictorial cylinders mounted frictionally thereon so as to revolve therewith and be capable of being individually held at rest, each of said cylinders having a corresponding plurality of pictorial faces of substantially the same angular dimension, forks normally idle that are movable toward the longitudinal axis of said shaft to engage each of said cylinders between their pictorial faces for holding the 55 same at rest, and adjustable cam wheels for actuating said forks in a timed relationship to the rotation of said cylinders.

2. Pictorial display apparatus including a 60 cylinder shaft, a plurality of individual pictorial cylinders mounted frictionally thereon

so as to revolve therewith and be capable of being individually held intermittently at rest, a guide plate for each cylinder, a forked holding plunger for each of said cylinders supported in said guide plates and movable to engage and temporarily hold their respective cylinders, a cam shaft parallel with said cylinder shaft, an adjustable cam wheel for each cylinder secured on said cam shaft in position to engage and actuate its respective holding plunger, and a drive shaft for intermittently driving said cylinder and cam shafts. 70

3. Pictorial display apparatus, including a shaft, a plurality of individual pictorial cylinders mounted frictionally thereon so as to 80 revolve therewith and be capable of being individually held at rest, said cylinders having a plurality of pictorial faces of equal dimensions with angular corners at the junction of said pictorial faces, a forked holding plunger 85 in position to engage a corner of each cylinder but held normally out of engagement therewith, a cam wheel for actuating said holding plunger, and means for rotating said cylinders and cam wheels for timing their 90 movement.

4. Pictorial display apparatus including a shaft, a plurality of individual pictorial cylinders mounted frictionally thereon so as to 95 revolve therewith and be capable of being individually held at rest, said cylinders having a plurality of pictorial faces of equal dimensions with angular corners at the junction of said pictorial faces, a holding plunger in position to engage and stop each cylinder but held normally out of engagement therewith, a cam wheel for actuating each holding plunger, said cam wheel having in its periphery equidistant recesses for receiving the heel 100 of the holding plunger when idle, and a peripheral surface following each recess for moving said holding bar into cylinder holding position, and means for rotating said cylinders and cam wheels for timing their movement. 110

5. Pictorial display apparatus, including a shaft, a plurality of individual pictorial cylinders mounted frictionally thereon so as to revolve therewith and be capable of being individually held at rest, said cylinders having a plurality of pictorial faces of equal dimensions with angular corners at the junction of said pictorial faces, a holding plunger in position to engage and stop each cylinder but held normally out of engagement therewith, a cam wheel for actuating each holding plunger, said cam wheel having in its periphery equidistant recesses for receiving the heel 115 of the holding plunger when idle, and a peripheral surface following each recess for moving said holding plunger into cylinder holding position, a plate mounted on each cam wheel for closing each recess individually in the periphery of the cam wheel and rendering the adjacent parts of the periphery of 120 125 130

the cam wheel continuous so as to prolong the holding position of the holding plunger, and means for rotating said cylinders and cam wheels for timing their movement.

- 5 6. Pictorial display apparatus, including a shaft, a plurality of individual pictorial cylinders mounted frictionally thereon so as to revolve therewith and be capable of being individually held at rest, said cylinders having 10 a plurality of pictorial faces of equal dimensions with angular corners at the junction of said pictorial faces, a holding plunger in position to engage and stop each cylinder but held normally out of engagement therewith, 15 a cam wheel for actuating each holding plunger, said cam wheel having in its periphery equidistant recesses for receiving the heel of the holding plunger when idle, and a peripheral surface following each recess for 20 moving said holding plunger into cylinder holding position, a plate mounted on each cam wheel for closing each recess individually in the periphery of the cam wheel and rendering the adjacent parts of the periphery 25 of the cam wheel continuous so as to prolong the holding position of the holding plunger, means for rotating said cylinders and cam wheels for timing their movement, and yielding means in each of said plates for frictionally but releasably holding it in its position 30 for actuating said holding plunger.

7. In a pictorial display apparatus the combination with a shaft having a plurality of individual pictorial cylinders mounted 35 frictionally thereon so as to revolve therewith and capable of being individually held at rest while said shaft continues to rotate, of means for separately interrupting the rotation of said cylinders including a cam wheel 40 for each cylinder each having spaced recesses in the rim thereof, and segmental plates pivotally secured to the sides of said wheels that are adjustable to move their cam surfaces into or out of alignment with the peripheral surfaces of said wheels.

8. In a pictorial display apparatus the combination with a shaft having a cylinder mounted frictionally thereon so as to revolve therewith and capable of being held at rest 50 while said shaft continues to rotate, of a plunger arranged to engage and disengage said cylinder, a heel to said plunger, a cam wheel having spaced recesses therein adapted to receive the heel of said plunger, a toe to 55 said heel extended out over a side of said cam wheel, and cam plates pivotally mounted on said wheel that are adjustable to engage or disengage said toe.

9. In a pictorial display apparatus the 60 combination with a shaft having a cylinder mounted frictionally thereon so as to revolve therewith and capable of being held at rest while said shaft continues to rotate, of a plunger arranged to engage and disengage 65 said cylinder, a heel to said plunger, a cam

wheel having spaced recesses therein adapted to receive the heel of said plunger, a toe to said heel extended out over a side of said cam wheel, cam plates pivotally mounted on said wheel that are adjustable to engage or disengage 70 said toe, a recess in each of said cam plates, and a spring pressed head in each recess for engaging notches in the side of the cam wheel to hold said cam plates in adjusted 75 position.

In witness whereof, I have hereunto affixed my signature.

GUSTAVUS W. ESCHENBACH.
